PULL-OVER JACKET

Sidne Koons, Clayton, Mo., assignor to The Grove Company, St. Louis, Mo., a corporation of Missouri

Filed Nov. 24, 1958, Ser. No. 53,487

Term of patent 7 years

(Cl. D3—25)

FIGURE 2 is a front elevational view thereof as it appears in flat position, the neck opening being shown untied to better show the underlying dickey; and

I claim:

The ornamental design for a pull-over jacket, substantially as shown and described.
